UNITED STATES PATENT OFFICE.

CHARLES K. PICKLES, OF PHILADELPHIA, PENNSYLVANIA, ASSIGNOR
TO JOHN A. BRILL, OF PHILADELPHIA, PENNSYLVANIA.

CURTAIN-FIXTURE.

SPECIFICATION forming part of Letters Patent No. 784,427, dated March 7, 1905.

Application filed October 29, 1903. Serial No. 179,102.

To all whom it may concern:

Be it known that I, CHARLES K. PICKLES, a citizen of the United States, and a resident of the city and county of Philadelphia, State of Pennsylvania, have invented certain new and useful Improvements in Curtain-Fixtures, of which the following is a specification.

My invention relates to fixtures for curtains, more especially those employed in street-railway or similar cars, although the same may be employed in other relations; and it consists of the means for guiding and restraining the movement of the curtain and secured to the lower end of the latter.

15 The objects of my invention and details of construction will appear hereinafter.

In the drawings forming part of this specification, Figure 1 is a front view of part of a curtain with my improved guide. Fig. 2 is a 20 section on the line 10 10 of Fig. 1, and Fig. 3 is a perspective view of one end of the rod.

The object of my invention is to provide a curtain-rod having guiding shoes and arms thereon with a rod, and specifically at the 25 lower end of the arms, to increase the efficiency of the guide-feet and to hold the end of the curtain so that it will entirely close the side opening of the car. The rod also acts to protect the curtain-rod proper and serves as 30 a protection against passengers' hats, &c., catching on the finger-pieces of the rod.

Referring to Fig. 1 of the drawings, 1 represents a curtain, only partly shown, which is adapted to close the space between car-stanchions and to be guided thereon.

Attached to the curtain, such as by the pocket 2, formed near the end of the curtain by means of a piece of material 3 sewed thereto, is the usual curtain-rod casing 4, on each 40 end of which are the guide-shoes 5. So far as my present invention is concerned, any desired gripping mechanism may be used in the casing for engaging with the stanchions or cables. The foot 5, which has the vertical 45 arms 6 and 7, is provided at the end of one or both of the arms (and I prefer the lower arm

at least) with a socket 8 to receive a cross-rod 9, which is secured therein on the feet at each end of the curtain-rod, preferably by screw-threads.

The rod 9 engages with the lower end of the curtain, and for this purpose it may be passed through the hem 10 of the curtain. The curtain may be cut away at 11, as is customary, to give room for the finger-pieces of the rod. 55

This construction not only keeps the guide-feet parallel, but carries the end of the curtain to the extreme of the side opening of the car and protects the finger-pieces.

Having described my invention, what I 60 claim is—

1. A curtain attachment having guiding-shoes, vertical guide-arms on said shoes, and a rod connected to the ends of said guide-arms.

2. A curtain attachment for railway-cars or 65 similar vehicles, having guide-shoes on the ends thereof, vertical guide-arms on said shoes, and a cross member connecting the lower ends of said guide-arms.

3. In a curtain attachment, a casing, shoes 70 to guide the same, guide-arms on said shoes having sockets, and a rod in said sockets, connecting the opposite arms of said shoes.

4. In a railway-car or similar vehicle, a curtain, a curtain attachment secured thereto, 75 having shoes on the ends thereof, guide-arms on said shoes, a rod connected with the lower portion of said curtain, and connecting the said guide-arms.

5. In a railway-car or similar vehicle, a curtain, a curtain attachment therefor, shoes to guide the same having downwardly-extending arms, a rod passing through a hem on the lower end of said curtain and connecting the opposite ends of said guide-arms. 80

Signed in the city and county of Philadelphia, State of Pennsylvania, this 16th day of September, 1903.

CHARLES K. PICKLES.
